UNITED STATES PATENT OFFICE.

WILLIAM E. MATTHEW, OF BUCYRUS, OHIO.

FUSEE.

SPECIFICATION forming part of Letters Patent No. 794,371, dated July 11, 1905.

Application filed September 6, 1904. Serial No. 223,562.

To all whom it may concern:

Be it known that I, WILLIAM E. MATTHEW, a citizen of the United States, residing at Bucyrus, in the county of Crawford and State of Ohio, have invented certain new and useful Improvements in Fusees; and I do hereby declare the following to be a full, clear, and exact description of the invention, such as will enable others skilled in the art to which it applies to make and use the same.

My invention has relation to signaling-torches commonly designated a "fusee," and my invention consists of certain novel features of combination and construction of elements, the preferred form of materialization whereof will be hereinafter clearly set forth, and exemplified in the claims appended.

The main object of my invention, among others, is to provide a torch or fusee designed to be used in railway signaling which will combine in a single torch the capacity of two or more separate and distinct torches or fusees. Inasmuch as my improved fusee is constructed to give off different-colored lights, each light burning for a definite or specified period of time—as, for instance, it may be arranged to first give off a red light as a danger-signal, which light will continue to burn for any desired length of time, ordinarily five minutes, to be followed by a green light, to last or continue to burn for an additional period of five minutes, more or less, as may be desired. It is obvious that additional colored lights may also be employed by increasing the capacity of the exterior casing or housing tube.

Other objects and advantages will be hereinafter set forth, reference being had to the accompanying drawings, which are made a part of this application, and in which—

Figure 1 shows a longitudinal central section of my combination colored fusee. Fig. 2 is a perspective detail view of the fusee proper, illustrating the method of assembling the combustible material employed to produce variegated flames. Fig. 3 is a sectional view taken on line 3-3 of Fig. 1. Fig. 4 shows a method of filling the fusee-tube by means of a specially-prepared funnel. Fig. 5 is a detail view showing the upper portion of the

casing filled with a combustible substance adapted to produce a different-colored light from that occupying the lower portion of the casing. Fig. 6 is a transverse section of Fig. 4 on line 6-6. Fig. 7 shows the exterior casing or housing with the lower portion filled with combustible substance designed to produce a light of a specific color and also showing the upper portion of the casing as being partly filled with combustible substance designed to produce a light of a distinctly different color.

Referring to the numerals on the drawings, each of which is employed to designate the same part throughout the several views, 1 designates the casing or housing, which is made in tubular form and is inclosed at its lower end by means of a weighted section or member 2, which latter is provided with a spear-like terminal or pointed extension 3, designed to take into the ground or the cross-tie, as the case may be, thereby holding the casing or tubular section 1 in a substantially upright position. The tubular member or casing 1 is also provided at its upper end with the closure or cap 4, intended to fit snugly over the end of the casing, excluding the moisture from the interior thereof. I dispose within the casing thus or otherwise constructed a filling of combustible material so prepared and disposed that said material will at the time of combustion give off a light of specified color. This result of producing a red, green, or other colored flame may readily be attained by proper preparation of the combustible matter, all of which is well known in the art, and my purpose, therefore, is to so graduate and assemble the prepared combustible material that one section of the filling in the tube or casing 1 shall last for a specified period of time before the next adjacent compartment or section of combustible matter shall have become ignited, and with this purpose in view I first provide a tube-like member fashioned from some waterproof material, as paraffin-paper or the like, and I constrict the lower end of said tube, as by twisting said end tightly together, as designated by the numeral 5.

In some instances I provide a fuse, as designated by the numeral 6, which I locate in the central portion of the tube of paraffin-paper or other waterproof substance, as designated in Fig. 2. After constricting the lower end of the tube of paraffin-paper or the like, as indicated by the numeral 5, the lower section 7 of said tube may be filled to the desired height by combustible substance and when ignited will give off a colored light of the desired character, and after the proper quantity has been disposed in the lower section 7—as, for instance, a quantity which will burn for a period of five minutes—the tube is twisted tightly upon itself, as designated by the numeral 8, which completely closes the section 7, separating it from the section 9 immediately above, which lower section may be filled to the desired extent with combustible material to give off another colored light. After the section 9 has been supplied with the requisite amount of combustible matter the tubular waterproof casing is again twisted sharply, as designated by the numeral 10, leaving the upper section 11 to be filled with combustible substance giving off an additional color when ignited, and after the section 11 has been properly filled the upper end thereof is completely inclosed and perfectly housed against moisture by tightly twisting the end of the tube, as indicated by the numeral 12, thereby leaving a section of the fuse 6 exposed to facilitate ignition.

In Fig. 1 the relative arrangement of the various parts is clearly set forth, and it is obvious that the fuse will insure that the material in each of the compartments 7, 9, and 11 will be ignited, and since a graduated or predetermined quantity of material has been supplied for each of said sections it follows that a light of different color is provided, the different colors to follow each other in succession, as required by the signaling-code.

Ordinarily a fusee supplied with two distinctly different lights will, it is thought, prove amply sufficient; but in the present application I have shown three separate compartments adapted to contain as many different combustible substances, whereby three lights of different color will be given off.

In Figs. 4 and 7 I have shown means for filling the exterior casing by utilizing a funnel of sufficient length to reach downward into said casing, so that the lower half thereof, more or less, may be filled with combustible substance designed to produce a specific colored light. By the construction shown in Figs. 4 to 7, inclusive, I am enabled to dispense with the special form of casing of paraffin-paper, as shown in Fig. 2, also dispensing with the necessity of a fuse designed to extend from one end of the exterior casing to the other. It will be observed by reference to Fig. 4 that I provide a funnel having a cylindrical discharging-nozzle or conveyer-pipe

14 and the flared upper end or receiving-section 15, as is common, the cylindrical portion 14 being of sufficient size to be loosely received by the casing.

It will be understood that the cylindrical section 14 is of sufficient length to reach down into the open end of the casing 1 to the middle portion thereof and that the combustible substance designed to occupy the lower end of the casing may be first introduced through the hopper-section 15, when it will pass into the lower end of the casing 1, and should more of the substance be introduced than will fill the space below the end of the cylinder member 14 the excess will clog and remain in the lower end of said cylindrical section and be removed therewith when the cylinder is withdrawn, leaving only the lower half of the casing supplied with the requisite amount of material to burn a specified time and to give off a specified color, as red, green, or the like. After the lower half of the casing is filled with the desired combustible substance, as designated by the numeral 16, the upper half 17 is placed in position by almost wholly withdrawing the cylindrical portion 14 from the casing, as shown in Fig. 7, and it is obvious, therefore, that the upper portion may be easily filled with the exact portion desired when any form of closure or cap section 4 may be introduced in place upon the casing.

It is desirable that the section 14 shall be truly cylindrical, whereby the contents will not become clogged therein as when being introduced into the lower end of the casing 1. It is found by practice that any excess of material beyond that required to fill the lower half of the casing will adhere to the walls of the cylindrical member 14 and, as before stated, be withdrawn when such excess of material may be placed back in the receptacle from which it was obtained and the same funnel used again for the introduction of combustible material designed to produce a light of different color from that first introduced, thus providing a signaling torch or fusee which will produce two distinctively-colored lights, and thus, in effect, provide two separate and distinct signals within one casing, a most desirable and valuable desideratum.

It is well known that only two lights are ordinarily employed—first, a red light to indicate "danger," to be followed by a green light, indicating "safety." It is therefore obvious that my varicolored fusee may be provided with any desired number of lights, and it is also obvious that any suitable method of introducing the differently-formed combustible material within the casing 1 may be adopted, and while I have described the preferred combination and construction of parts deemed necessary in illustrating my invention I desire to comprehend all equivalents and substitutes which may fairly fall within the scope of my invention.

What I claim as new, and desire to secure by Letters Patent, is—

1. A fusee or signaling-torch consisting of a body portion or holder, an interior casing, 5 combustible material carried by said casing, said material being arranged in sections to burn a specified period of time, each section being isolated by twisting the interior casing at each end of each section of combustible material, and a fuse running through the several separated sections and extending from the twisted outer ends of the end section, all combined substantially as and for the purpose set forth.
  - 15 2. A fusee or signaling-torch comprising an outer and inner casing, combustible material carried by said inner casing, means to separate said combustible material into sections, each section producing a different-colored light 20 and adapted to burn a specified time and a fuse common to all of said sections substantially as and for the purpose set forth.
  - 25 3. In a fusee, an outer and inner casing, said inner casing being restricted at intervals to separate the same into sections, combustible material carried by each of said sections, the contents of each section producing a predetermined color, and means to successively ignite said sections, substantially as and for the 30 purpose set forth.
  - 35 4. A signaling-torch or fusee comprising a suitable casing 1, having an anchoring-stem in its lower end and a closure for its upper end, combined with a casing of waterproof material adapted to be filled in sections with combustible material, each section being separated from the other by twisting the said waterproof casing and a fuse running through
- 40
- the several separated sections of combustible material, substantially as specified and for the purpose set forth.
5. In a signaling-torch or fusee, an exterior casing and means to anchor the same in an upright position, combined with an interior casing of waterproof material, said interior casing being filled with combustible material arranged in sections, each section being isolated by twisting the waterproof casing at each end of each section, and a fuse running through the several separated sections and extending from the twisted outer ends of the end sections, substantially as specified and for the purpose set forth.
  - 45 6. A fusee or signaling-torch comprising an outer and inner casing, combustible material 50 in differently-colored sections carried by said inner casing, each section being held separate or isolated from the next succeeding section by constricting the inner casing at each end of each section of material, in combination with a fuse common to all of said sections, as set forth.
  - 55 7. In a fusee, an outer and inner casing, the inner casing being adapted to carry and separate material to produce light of the desired 60 color and durations and a fuse coöoperating with said material and designed to successively ignite the separated sections thereof, as and for the purpose set forth.

In testimony whereof I have signed my name to this specification in the presence of two subscribing witnesses.

WILLIAM E. MATTHEW.
